INVENTOR

WITNESS: *J.W. Ely.*

BY *Victor J. Evans*

ATTORNEY

UNITED STATES PATENT OFFICE.

WILLIAM G. WILSON, OF WEST NEW BRIGHTON, NEW YORK.

ANGLE RAIL-BAR.

1,370,390.

Specification of Letters Patent.

Patented Mar. 1, 1921.

Application filed November 22, 1920. Serial No. 425,860.

To all whom it may concern:

Be it known that I, WILLIAM G. WILSON, a citizen of the United States, residing at West New Brighton, S. I., in the county of 5 Richmond and State of New York, have invented new and useful Improvements in Angle Rail-Bars, of which the following is a specification.

This invention relates to angle rail bars 10 and one of the principal objects is to produce a device of this nature which shall be simple of construction, cheap to manufacture and highly efficient for the purpose for which it is designed.

15 Another object is to produce a device of this nature which will more effectively prevent breaking-down at the joint of the rails, and to keep the rails in alinement at all times under all conditions.

20 Another object is to provide a device of this nature with means whereby the nut of the lower securing bolt will be readily accessible for removal and may be removed by the same wrench as the nuts of the upper 25 bolts.

With these and other objects in view which will be more apparent as this specification proceeds, the invention consists in certain novel construction and combination 30 and arrangement of parts the essential features of which are hereinafter fully described and claimed and are shown in the accompanying drawing forming part of this specification, and in which:

35 Figure 1 is a side elevation of the improvement applied.

Fig. 2 is a vertical sectional view of my improvement on line 2—2 of Fig. 1.

Like characters of reference refer to like 40 parts in all views.

This invention contemplates providing angle bars for clamping rails at their joints said bars gripping the web and lower portions of the rails and extending under the 45 rails so as to be connected below the joint of the rails as well as to the webs of the rails, one of the angle bars of each pair being provided with a portion under the rail extending out flush with the edge of the 50 lower flange so as to expose the nut of the

lower fastening bolt so that it may be readily removed either by splitting with a cold-chisel or by means of the same wrench that is used on the other bolts.

Referring to the drawing more in detail, 55 10 and 11 represent rails of the ordinary type the ends of which meet or nearly meet forming a joint at 12.

The rails 10 and 11 are gripped between two angle bars 13 and 14 which are cut 60 away at 15 where they fit against opposite sides of the web of the rail. Bolts 16 provided with nuts 17 clamp the members 13 and 14 to the rails and pass through the cut away portions 15 so as to effect a springy 65 tension of the members against the rails. The lower portions of the members 13 and 14 embrace the lower flanges of the rails and extend thereunder at their central portions 18, the members being cut away at 19 for 70 the ties. Portions 18 are provided with strengthening ribs 20 and downwardly extending flanges 21 which do not quite meet below the rails.

The extension 21 of member 14 is elongated 75 and bent parallel with portion 18 as at 22 and then upwardly at 23, merging at its upper end into the side of the member 14 opposite the lower rail flange. A bolt 24 passes through the flanges 21 and 23, the 80 position of the flange 23 effecting exposing of the nut 25 of the bolt 24. It will thus be seen that the nut 25 is readily accessible for removal by any suitable means as for instance by the same wrench that removes 85 nuts 17.

The members 13 and 14 are cut out at 26 to form notches for the reception of the spikes which secure the rails to the ties.

While I have described what I deem to be 90 the most desirable embodiment of my invention, it is obvious that many of the details may be varied without in any way departing from the spirit of my invention, and I therefore do not limit myself to the exact 95 details of construction herein set forth nor to anything less than the whole of my invention limited only by the appended claim.

What is claimed as new is:—

In a device of the class described, the 100

combination of a pair of angle bars formed to embrace a rail joint and provided with spaced substantially vertical flanges below the rails, one of said flanges being bent back 5 upon itself and upwardly to form a second flange exposed from the side of the respective angle member, bolts passing through

said members and said rails, and a bolt passing through said spaced flanges and through the said second flange so as to expose the 10 nut thereof for ready manipulation.

In testimony whereof I have affixed my signature.

WILLIAM G. WILSON.
